Albert W. Morse
INVENTOR.

BY Walter S. Wallheim
ATTORNEY

UNITED STATES PATENT OFFICE

ALBERT W. MORSE, OF FOREST HILLS, NEW YORK

NEBULIZER OF LIQUIDS

Application filed October 10, 1930. Serial No. 487,793.

This invention relates to nebulizers of liquids, that is, apparatus for causing liquids to assume the form of an extremely fine mist; and the invention particularly relates to 5 nebulizers of the free swirling type herein-after disclosed wherein the swirling action is obtained not by moving parts or by stationary baffles in the discharge passage, but by the direction of admission into the passage.

10 In nebulizers of this kind free action is obtained by the tangential direction of inlet orifices into a so-called swirl chamber within the discharge nozzle, substantially as described in Patent #876,108 issued January 7, 15 1908, to Stringham and Elmendorf.

Liquid nebulizing devices of the kind which depend upon liquid pressure to operate, have a maximum available capacity under a given liquid pressure which is 20 restricted by the total area of the inlet orifices to the swirl chamber. To increase the capacity under a given pressure, it is necessary to bore out these orifices. To decrease the capacity, it is necessary to throttle the liquid 25 pressure by a valve in the liquid supply pipe. When this valve is throttled, the liquid pressure is decreased at the nozzle or more particularly at the inlet orifices to the swirl chamber. As this pressure is decreased, the 30 nebulizing becomes coarser and coarser, due to the fact that the swirling force is decreased. Eventually this force becomes so small that it is not sufficient to overcome fluid tension and no nebulizing effect whatever is produced.

In a Patent #1,439,320 issued to me on December 19, 1922, I have provided the discharge nozzle of nebulizers with a control of its inlet orifices to the swirl chamber for the 40 purpose of maintaining a constant liquid pressure at the outlet of the nozzle by varying the size of the inlet orifices to the swirl chamber to suit the capacity desired, the swirling force remaining constant.

45 It is the principal object of this invention to provide a more efficient means for regulating the inlet for the liquid to the swirl chamber than is disclosed in the aforementioned Patent #1,439,320.

50 Another object is to provide inlet means

to the swirl chamber of a kind which are readily cleaned of obstructions, and which by their shape are less likely to become clogged.

Further objects of the invention will appear in the following specifications in which a preferred form of nebulizer is described as applied to fuel oil burning apparatus.

The invention is illustrated by means of the accompanying drawing, in which

Fig. 1 is a vertical longitudinal sectional view of a burner;

Fig. 2 is a transverse cross sectional view taken along the plane of line 2—2 in Fig. 1;

Fig. 3 is an enlarged fragmentary sectional view of the nebulizer itself forming part of the burner and its regulating means; and

Fig. 4 is a cross sectional view along the plane of line 4—4 in Fig. 3.

Like characters of reference denote similar parts throughout the several views and the following specifications.

10 is a hollow casing of substantially L shape, one branch 11 of which is tapped at 12 for an air supply pipe 13, communicating with the interior of the casing. The end portion of the casing adjacent branch 11 is tapped to receive a plug 14, which is bored out centrally to receive a tubular spindle 15 which is in axial alignment with a center or main branch 16 of the casing 10 in communication with the air supply pipe 13.

17 is an elbow screwed into an extension of the spindle 15 exteriorly of the casing 10, having a bonnet 18 and nut 19 within which by screw threaded contact with the bonnet in the usual manner is reciprocated a long regulating stem 20 which projects into the forward end of the spindle 15. Elbow 17 has screwed into its inlet end a fuel supply pipe 21.

The forward end of the spindle 15 projects outside of branch 16 and is interiorly threaded to receive a nebulizer 23.

Nebulizer 23 is shaped polygonally at 24 to facilitate screwing the same into the spindle 15. 25 is a cylindrical recess at the inner face of the nebulizer, its bottom 26 being preferably angularly disposed forming 100

a conical roof to the recess, having in its apex a circular outlet 27.

28 is a tubular bushing pressed tightly into the recess 25, one end flush with the end of the nebulizer and its other end abutting and having the same angle as the bottom 26 of the recess. 29 is a fine slot through the wall of the bushing 28 tangentially disposed to the inside of the bushing as clearly shown in Fig. 4. The forward end of the regulating stem 20 projects into the inside of the bushing and is in sliding contact therewith, its face 30 being chamfered to correspond with the conical bottom 26 of the recess 25 and forming a swirl chamber 31 therewith.

The outside of the nebulizer 23 is provided with a small circular chamfer at 32 concentric with the outlet 27.

33 is a cup-shaped cap threaded interiorly to fit a threaded end of branch 16 of the casting 10. Cap 33 is provided with a circular opening 34 of a diameter smaller than the outside of the nebulizer 23. 35 is a lock nut, also in threaded engagement with branch 16, for the purpose of holding cap 33 in any fixed relation to the nebulizer.

The operation of the device is as follows: Oil is admitted into the burner, under pressure, through supply pipe 21 into the hollow spindle 15. Then through slot 29 into the swirl chamber 31. Owing to the direction of the inlet orifice or slot 29, tangential with respect to the wall of the swirl chamber, the oil is being given a swirling motion, and is finally expelled in a rotary swirl from outlet 27.

Air is admitted also under pressure, into the interior of casing 10 by means of pipe 13, whence it is deflected by cap 33 towards the spray of oil issuing from outlet 27, resulting in a vapor of high combustive qualities.

If it is desired to cut down the capacity of the nebulizer, it is only necessary to screw the regulating stem 20 further towards the bottom of the recess 26, when the stem 20 will gradually cut down the length of the slot 29 to a more or less degree as desired. It will be noted that the full liquid pressure is maintained right at the slot on account of which the nebulizing action is not in the least impaired. By this means of regulation of the inlet orifice to the swirl chamber fuel oil may be used at much higher pressures than heretofore. In devices provided with circular inlet orifices, the orifices have a tendency to clog up, while where the slot as disclosed is employed, it is only necessary to withdraw the regulating stem 20 a little further. This eliminates the necessity of removing the nozzle and the use of a fine wire for cleaning the orifices, the practice employed heretofore. The width of the slot 29 may be made wider where particularly heavy oils are used. In actual practice it

was found that even with relatively high fluid pressure, the flow can be regulated down to almost nothing, always obtaining an excellent spray until the annular space between bottom of the recess and face of regulating stem, or in other words, the height of the swirl chamber, is less than .01".

The angle at the bottom of the recess 25 may be varied from a right angle to a very acute one, and whatever angle is used, there is a perfect, unobstructed smooth flow of liquid toward the outlet no matter to what minute size the swirl chamber is reduced.

While I have shown the slot 29 milled through the wall of the bushing 28 exactly tangential to its cylindrical interior, it is obvious that this is, where commercial production is concerned, practically impossible, and will usually be made approximately .01" or more away from the extreme side of the inner part of the bushing, so by tangential is meant substantially tangential sufficient to induce a rotary swirl.

It is understood that various other changes in the form, proportion and minor details of construction may be resorted to without departing from the principle or sacrificing any of the advantages of the invention as defined in the appended claims.

Furthermore, while the nebulizer is shown in combination with an oil burner, it is understood that the invention may be used in connection with any device utilizing the nebulizing principle.

What I claim as new, is:

1. A nebulizer of liquids comprising a structure having a recess at one end with a central outlet through to its other end, a cylindrical bushing pressed into the said recess having a slot through its entire length tangential to the center of the bushing, and a regulating stem slidingly engaging the center of the said bushing.

2. A nebulizer of liquids comprising a structure having a recess at one end and a central outlet, a hollow bushing within the said recess extending through the entire depth thereof having a slot tangential to its center extending through its entire length, and a stem slidingly and reciprocatingly engaging the center of the said bushing.

3. A nebulizer of liquids comprising a structure having a recess at one end with a central outlet through to its other end, a cylindrical bushing pressed into the said recess extending through the entire length of the said recess having a slot through its entire length tangential to the center of the bushing, and a regulating stem slidingly engaging the center of the said bushing.

In testimony whereof I have hereunto set my hand.

ALBERT W. MORSE.
